UNITED STATES PATENT OFFICE.

WILLIAM S. JENNINGS, OF OREGON CITY, OREGON.

PUMP.

Application filed February 5, 1921. Serial No. 442,719.

This invention relates to pumps, and comprehends a construction designed for use in several capacities, as for instance, a device for pumping heavy wood pulp, an irrigating 5 pump, or it may be used as a rotary water or steam engine.

The invention embodies amongst other features a filtering chamber of novel construction which communicates with the inlet 10 of the pump, and the novel and efficient means for lubricating the sliding piston of the rotor, the invention resides in the construction and combination, and arrangement of parts as claimed.

15 In the drawings forming part of this application like numerals of reference indicate the similar parts in the several views and wherein:—

Figure 1 is a front elevation of my im- 20 proved pump;

Figure 2 is a side elevation;

Figure 3 is a transverse sectional view and Figure 4 is a detail longitudinal sec- 25 tional view.

20 Referring to the drawings in detail 10 indicates the bed or supporting structure for the cylinder 11 which is bolted or otherwise suitably secured to the bed as shown. Arranged eccentrically within the cylinder 11 30 is the rotor 12 carried by the shaft 13 which passes longitudinally through the cylinder and equipped with suitable stuffing boxes 14. The cylinder is provided with inlet open- 35 ings 15 and an outlet opening 16. Arranged between these openings and extending longitudinally of the cylinder is a packing 40 17 which is yieldably held in contact with the periphery of the rotor to provide a tight connection between the rotor and cylinder at this point.

45 Arranged above the packing 17 and secured to the cylinder in any suitable manner is a plate 18 which supports a plurality of screws or other suitable adjusting ele- 50 ments 19 by the instrumentality of which the tension of the springs 20 may be varied, these springs being interposed between the packing 17 against which they bear and the plate 18. Manifestly, the springs 20 swing 55 to maintain the packing in effective contact with the rotor. The shaft 13 is pro- 60 vided with a longitudinal slot 22 through which the sliding piston 23 operates, the rotor being provided with slots 24 through 65 55 which the piston 23 slides. The piston is made up of two sections which are con-

nected by a spring 22' interposed between the sections and operable to hold the piston section against the wall of the cylinder. Arranged at each side of the piston 23 are 60 guide rollers 25, the latter being arranged in pairs on the rotor at diametrically opposite points. The piston 23 is provided with a roller 26 which has each end contacting with the inner periphery of the cylinder, 65 while each end of the piston is also equipped with a spring pressed packing 27 which projects from the end of the piston to bear against the wall of the cylinder. The shaft 12 is provided on each side with a lubricant 70 chamber 28, these chambers surrounding the slot in said shaft and being supplied with lubricant from a plurality of lubricant containing cups 30, the latter communicating with the opposite ends of the chamber 28 75 by means of passages 31 leading from the cups 30. The piston 23 is provided with a plurality of oil slots 32 and 33 respectively, these slots leading from the ends of the piston to a point in close proximity to the 80 transverse center of the piston, the corre- 85 sponding ends of the slots opening at the opposed sides of the piston as shown. In other words, the slot 32 is supplied with oil from one of the chambers 28 of the shaft 13, while the slot 33 is supplied with oil from the other chamber 28 of said shaft. It is obvious that as the piston slides through the rotor the slots 32 and 33 alternately communicate with their respective chambers 28 90 for the purpose stated. The slots serve to lubricate the opposed sides of the piston to minimize friction during the sliding move- 95 ment of the piston, and also to lubricate the rollers 25 and 26. The shaft 13 projects beyond one end of the cylinder and has as- 100 sociated therewith a belt pulley 35. A sup- 105 ply pipe for the pump is provided as shown at 36, which has suitable communication with the inlet opening 15.

Leading from the outlet opening 16 of the cylinder is an outlet pipe 53, while projecting from the pipe is an elongated casing 54 in which is arranged a valve 55 including a thread stem 56, the valve 55 controlling 105 communication between the cylinder and the outlet pipe 53. While the invention is primarily intended for pumping heavy wood paper pulp, it is obvious that it can be most advantageously used for other pur- 110 poses and that by eliminating the filtering chamber and the outlet pipe 53 together

with the valve 55 the construction can be used as a rotary engine.

While it is believed that from the foregoing description the nature and advantages of the invention will be readily apparent, I desire to have it understood that I do not limit myself to what is herein shown and described and that such changes may be resorted to when desired, as fall within the scope of what is claimed.

What I claim is:—

A pump of the character described comprising a cylinder having an outlet and inlet opening, a rotor mounted eccentrically within the cylinder, a packing disposed between the inlet and outlet openings, a plate over the packing and secured to the cylinder, springs between the plate and packing, adjustable elements carried by the plate and 20 engaging the springs for yieldably holding the packing in engagement with the periph-

ery of the rotor, a shaft supporting the rotor and being provided with a longitudinal slot aligned with like slots formed in the rotor, a two part spring connected and 25 pressed piston mounted for slidable movement in the aligned slots, each part being provided with a longitudinally arranged oil slot leading from an oil chamber in the shaft to the outer ends of said parts, guide 30 rollers for the piston and being disposed in pairs in the slots of the rotor at diametrically opposite sides thereof, a roller at each end of the piston and being disposed in the path of oil from the oil slots, and spring 35 pressed packing projecting from the respective ends of the piston as and for the purpose specified.

In testimony whereof I affix my signature.

WILLIAM S. JENNINGS.
